Inventor:
Howard F. Fick

UNITED STATES PATENT OFFICE.

HOWARD L. FISCHER, OF ST. PAUL, MINNESOTA.

PENCIL.

1,427,729.

Specification of Letters Patent. Patented Aug. 29, 1922.

Application filed May 13, 1921. Serial No. 469,295.

To all whom it may concern:

Be it known that I, HOWARD L. FISCHER, a citizen of the United States of America, residing in St. Paul, in the county of Ramsey and State of Minnesota, have invented new and useful Improvements in Pencils, of which the following is a specification.

My invention relates to mechanical pencils designed primarily with a separable lead 10 propelling means. It is very desirous in mechanical pencils using a precious metal barrel or casing to provide means which allows the propelling means to be entirely separable from the casing, so that should the 15 propelling mechanism need to be repaired or replaced, this can be readily accomplished without making it necessary to send the pencil back to the factory or in any way affecting the enclosing casing.

20 It is essential that a pencil of this nature be so designed as to give the user continuous service and to accomplish this I have made my pencil with the parts of the propelling means separable from each other. 25 The propelling means consists of only a small part or parts the operation of which is apparent to the user on taking the mechanism apart thus allowing one to use the pencil in a more intelligent manner.

30 A feature of the invention is in the means for locking the parts of the propelling mechanism together to hold them firmly in position in the casing in position for use. This locking means is associated between the 35 magazine closure and the operating head of the pencil while the closure forms means for holding the entire operating mechanism positioned within the casing. The locking means is rotatably secured to the magazine 40 closure and is attached to the same so as not to be separated therefrom. The locking member is adapted to rotate with the operating head when the mechanism is operated.

In the drawings forming part of this 45 specification:

Figure 1 is an enlarged longitudinal cross sectional view of the pencil.

Fig. 2 illustrates a portion of the operating mechanism removed from the casing 50 part of which is in cross section.

Fig. 3 illustrates a central operating member of the propelling mechanism withdrawn from the mechanism.

Fig. 4 is a detail of the rear end of the 55 pencil.

In the drawings A represents my pencil

which is provided with an enclosing casing or barrel 10 preferably of a precious metal tubing such as gold or silver which is adapted to house the lead operating mechanism B. 60 The forward end 11 of the pencil casing 10 is wedged to simulate the conical end of the ordinary writing pencil and is provided with an opening 12 in the apex through which the marking lead 13 passes as it is 65 projected by the lead propelling mechanism B.

The lead propelling mechanism B consists of a tubular threaded member 14 to one end of which is secured a spacing or stop 70 washer 15, while a closure collar 16 is secured to the other end of the member 14. It is obvious that these members 15 and 16 can be secured or attached to the member 14 rigidly in any suitable manner. 75

The washer member 15 forms a shoulder and spacing element to hold the inner member 14 spaced from the casing 10 and the closure 16 which is formed with a threaded portion 17 engages a threaded collar 18 80 positioned in the rear of the large end 19 of the barrel or casing 10, thus the member 14 is held firmly in the casing of the pencil A against rotation or longitudinal movement and in position to form an annular 85 space or magazine 20 for extra marking lead between the member 14 and the wall of the casing 10.

A collar 21 is rotatably secured to the closure member 16 by means of a projecting portion having an inturned end 22 which is formed integral with the body portion 16 to hold the collar 21 freely rotatable in relation to the member 16. The outer surfaces of the members 16 and 21 are 90 covered by annular bands 23 and 24 respectively which are formed of tubing of the same metal as the casing 10 so that if the casing 10 is of gold, the bands 23 and 24 would be of gold while the parts 16 and 21 100 can be formed of any suitable cheaper material. The bands 23 and 24 are securely attached to the members 16 and 21 while the band 23 is adapted to project over the edge of the member 21 so as to cover the joint 105 between these two members. This allows for the forming of a practically invisible joint between these members.

The operating member 25 of the mechanism B extends axially through the member 14 and is held centrally positioned at its forward end therein by the opening 26 in

the collar 15. This member is adapted to carry the lead driving member C which extends through the longitudinal slot 27 in the member 25 so as to engage the threads of the member 14. The lead carrying or driving member C is formed with resilient ends forming a frictional engagement between the members 14 and 25 and to compensate for any wear between these members. The resilient ends of the lead carrier C also allow the marking lead to be slipped back into the casing by direct pressure against the projected end of the same. Such pressure causing the lead carrier to slip over the threads and allow the lead to be protected.

The operating member 25 is rigidly attached to the nipple 28 which projects from the operating head 29 and the operating head is rigidly attached and secured to the collar 21 by the threaded portion 30 formed thereon which engages with internal threads 31 formed in the outer end of the collar. By firmly engaging collars 23 and 24, the operating head 29 can be attached or disengaged from the member 21. When the operating head 29 is secured to the member 21 and the mechanism B is operated, the member 21 and its collar 24 is adapted to operate with the operating head 29.

A suitable recess 32 is formed in the operating head 29 which is adapted to receive an eraser 33. In order that the eraser may be enclosed and protected, a suitable cap 34 is provided, if it is desired, which engages the outer surface of the operating head frictionally or otherwise in a manner to rigidly connect the cap and the operating head together, so that by rotating the cap 34 it will rotate the operating head 29 and thus operate the mechanism of the propelling means B of the pencil A.

The essential features of this invention reside in means for locking the operating parts of the lead propelling mechanism together at the rear end of the pencil casing 10 in a manner so that the parts of the propelling mechanism can be separated when desired from each other and also so that the inner parts can be covered by a suitable tubing or incasing bands of the same metal as the casing of the pencil A, still allowing the parts to be freely operated and disengaged from each other when it is desired. This construction allows the entire propelling mechanism to be removed from the pencil casing to leave the same entirely empty by firmly engaging the bands 23 and 24 and disengaging the threaded portion 17 of the member 16 from the collar 18 of the pencil. When the parts are so engaged the magazine chamber 20 is also opened so as to expose the extra marking lead therein. It is, however, unnecessary to remove the entire lead propelling mechanism to refill the pencil, but by separating the inner or operating mem-

ber 25 by disengaging it from the collar 21 a new marking lead can be inserted in the member 25 which is again replaced ready for operation.

What I claim as new and desire to secure by Letters Patent is:—

1. A pencil including a casing, a separable lead propelling means and connecting means interposed between the parts of said propelling means, rotatably secured against disengagement to one part of said propelling means in a manner to hold the parts as a unit in or out of said casing, and permit separation of the parts from each other. 75

2. A pencil comprising a casing, a separable lead propelling means spaced from said casing to form a lead magazine about said propelling means, a magazine closure secured to one member of said propelling means, an operating head secured to another member of said propelling means, and a connecting member forming an extension of said closure adapted to secure the members of said propelling means together. 80

3. A pencil including a casing, a lead propelling means formed of sections removable selectively or collectively from said casing, and means adapted to lock the sections of said propelling means together, exposed at the rear end of said casing between the rear 95 ends of the lead propelling sections. 90

4. A pencil including a casing, a sectional lead propelling unit, means for holding said unit collectively within said casing, an operating head and means interposed and exposed between said unit holding means and said head, adapted to separably lock the sections of said unit together. 100

5. A connecting means for the sections of a mechanical pencil having a separable lead propelling unit including a closure collar secured to the outer section of said unit, and a collar inseparably connected to said closure adapted to engage the inner section of said unit to hold the sections operatively together and separable from each other. 105 110

6. A connecting means for a separable lead propelling mechanism of a mechanical pencil, comprising a member inseparably secured to one portion of said propelling mechanism adapted to releasably engage the other portion of said propelling mechanism to hold the portions freely rotatable in operating position. 115

7. A mechanical pencil, having a casing, 120 a lead propelling unit formed of separable sections adapted to be enclosed in said casing, means for spacing said propelling unit from said casing to form a magazine space thereabout about said propelling unit, a closure for the magazine, a sleeve extending from and secured to said closure adapted to hold the operating sections of said unit in position in said pencil. 125

8. A pencil including a casing, a remov-

- able sectional lead propelling means, and a sleeve extending from the rear of said pencil and interposed between said casing and the operating end of said propelling means 5 adapted to secure the sections of said propelling means together for operation and to permit the parts to be removed collectively or selectively from said casing.
9. A pencil comprising a casing, a sectional lead propelling unit, and means for collectively and selectively securing the sections of said propelling unit within said casing, said securing means extending from the rear end of said casing.
10. 10. A pencil having a sectional lead propelling unit, a casing for enclosing said unit, means at the rear of said casing for securing said unit in said casing with its sections collectively or selectively removable, 20 an eraser recess in one of the sections, and a cap adapted to form the operating head for said unit and to conceal the eraser.
11. A pencil comprising a casing, a threaded member means fixed to the ends of
- said threaded member adapted to space it in 25 said casing to form a circular magazine thereabout, said spacing means on the outer end of said threaded member being adapted to detachably secure said threaded member in said casing, an operating member, having a 30 lead carrier, adapted to extend through said threaded member, an engaging head formed on said operating member, an eraser recess formed on said engaging head, a cap adapted to removably engage said head to conceal 35 the eraser, and a locking sleeve adapted to engage said head, secured to said rear spacing means on said threaded member.
12. A pencil including, a sectional lead propelling means, a casing for enclosing 40 said propelling means, and means secured to one of the sections adapted to secure the sections in said casing selectively and collectively removable, said means forming an extension of said casing and adapted to be engaged to remove the sections. 45

HOWARD L. FISCHER.
